UNITED STATES PATENT OFFICE.

ROBERT T. SUDDENDORF, OF CINCINNATI, OHIO, ASSIGNOR TO WITT CORNICE COMPANY, OF CINCINNATI, OHIO.

WASTE RECEPTACLE.

Application filed February 8, 1924. Serial No. 691,409.

To all whom it may concern:

Be it known that I, ROBERT T. SUDDENDORF, a citizen of the United States, and a resident of Cincinnati, in the county of 5 Hamilton and State of Ohio, have invented certain new and useful Improvements in Waste Receptacles; and I do hereby declare the following to be a full, clear, and exact 10 description of the invention, such as will enable others skilled in the art to which it appertains to make and use the same.

This invention relates to improvements in waste receptacles and more particularly to the closure structure therefor,—one object of 15 the invention being to provide a duplex closure structure embodying swinging doors which shall be independently supported and in which each door member shall be operable to retain the other door member in normally closed position and permit either door member to be opened inwardly and automatically cause both door members to afterwards assume normal closed positions without the employment of weights.

With this and other objects in view, the invention consists in certain novel features of construction and combination and arrangement of parts as hereinafter set forth and pointed out in the claims.

In the accompanying drawings,

Figure 1 is a view of a waste receptacle showing an embodiment of my invention.

Figure 2 is a transverse sectional view of the hood portion of the receptacle, and

Figure 3 is a bottom plan view of said hood portion.

The body portion 1 of the receptacle may be made angular in cross section and the hood portion 2 has a general conical shape 40 with flat tapering sides 3—3 and 4—4 connected at the top or apex of the hood by a cross member 5 having depending flanges 6—6 suitably secured to portions of the sides 4—4 of the hood. The several side-members 45 of the hood are provided near the larger lower end of the latter with inwardly projecting flanges 7 by means of which the hood may be supported upon the upper edges of the body portion of the receptacle.

The side members 4—4 of the hood are made with tapering openings 8 which are normally closed by swinging doors 9—9. These doors are hinged at their upper smaller ends to the flanges 6—6 of the 50 cross member 5 of the hood and are pro-

vided with re-inforcing flanges 10 at their side and bottom edges to be normally disposed parallel with similar re-inforcing flanges 11 which project inwardly from the side and bottom edges of the door openings 8.

The provision of the cross member or bridge piece 5 with its flanges 6 reinforces the apex of the hood so that it will retain its form notwithstanding the rough usage 65 to which waste receptacles in public places are subjected. The doors are independently hinged immediately adjacent the member 5 so that large doors may be used and the strain upon their hinges will be minimized 70 so that the doors will operate easily and smoothly at all times.

To the inner faces of the respective doors, brackets 12 are secured and located comparatively short distances from the free lower 75 edges of said doors. Each bracket 12 is provided at its respective ends with inwardly projecting lugs or ears 13 and the lugs or ears of one bracket are connected with the lugs or ears of the other bracket by 80 means of curved bars 14,—the ends of which bars have pivotal connection with the lugs or ears of the brackets.

With the construction and arrangement of parts above described, the two independently 85 hinged doors will so cooperate with each other that each will be retained in normal closed position by the other; that when one door is opened inwardly the other door will be caused to swing outwardly, and that when 90 released both doors will swing to closed position, one door moving in an outward direction and the other in an inward direction.

It will be readily noted, upon reference to Figs. 1 and 2, that the doors may swing 95 through the respective door openings and that the connecting bars are rigid although they are pivoted to the doors in order to accommodate the relative eccentric swinging 100 of the doors. When an article is to be deposited in the receptacle, either door is pressed inwardly and the door opening is thereby cleared for the passage of the article which is dropped through the opening. When either door is opened, the force applied thereto is transmitted to the other door 105 through the connecting bars so that said other door is swung upwardly and outwardly as shown by dotted lines in Fig. 2. The outwardly and upwardly swung door 110

then acts as a weight to at once return the inwardly swung door to the closed position when the opening force is withdrawn therefrom, and each door acts as a counterweight to the other door whereby both doors are normally held in closed position and neither door can be opened without imparting a corresponding movement to the other door.

Having fully described my invention what I claim as new and desire to secure by Letters Patent, is:

1. A hood for a waste receptacle, comprising a plurality of convergent sides, two of said sides having openings convergent upwardly, doors hinged on pivots out of alignment with each other at the opposite sides respectively of said hood and swingable through said openings, and a rigid bar extending from one door to the other and hinged to both.

2. A hood for a waste receptacle having upwardly converging sides, two opposite

sides being provided with door openings, a bridge member at the apex of the hood having downwardly extending flanges at its edges secured to the upper ends of the sides of the hood, doors independently hinged at their upper ends to the hood and movable through said door openings, each door being hinged immediately adjacent a side flange of the bridge member and the hinges of the respective doors being out of alignment with each other, brackets secured to the inner sides of the doors near the lower ends thereof, and a rigid bar extending between the doors and having its ends pivoted to the brackets.

In testimony whereof, I have signed this specification in the presence of two subscribing witnesses.

ROBERT T. SUDDENDORF.
